UNITED STATES PATENT OFFICE

2,231,425

OIL WELL TESTING DEVICE

Max L. Johnston, Orange, Tex., assignor to Shell Development Company, San Francisco, Calif., a corporation of Delaware

Application July 14, 1939, Serial No. 284,499

4 Claims. (Cl. 166—1)

This invention relates to improvements in oil well testing devices and especially to those well testing devices commonly known as formation testers.

Although many formation testers have been developed for commercial use, these have several common disadvantages. The most important is that in the event of the well's becoming lively when tested, circulation of drilling mud to kill the well necessitates discarding the test sample. In some cases it would be very desirable to circulate drilling fluid in the hole to prevent freezing or sticking of the tool or drill string in the borehole while taking the sample. Further, in soft formations a leak frequently develops at the seat of the packer which spoils the test.

Therefore, it is an object of this invention to provide an improved formation tester comprising a device containing a valve mechanism to define a chamber for storing a formation sample and to permit circulation of mud fluid without discarding the sample.

It is another object of this invention to provide a formation tester with an auxiliary inflatable packer capable of utilizing well pressures to prevent leaks between the tester and the walls of the hole.

Other objects of this invention will be apparent from the following description taken in reference to the drawing, wherein:

Figure 1 is a vertical cross section view of the lower portion, wherein the right hand side of the center line in the drawing shows the control valve in open position and the left hand side shows the control valve in closed position.

Figure 2 is a vertical cross section view of the upper portion, wherein the right hand side of center line shows the valves in position for circulating drilling mud while the left hand side of the drawing shows the compound valve mechanism in position for testing.

The present device may be applied to either a rotative or a stationary testing tool and is also applicable whether the tester valve mechanism or control valve is operated by vertical or rotary movement. However, the device is preferably applied to a rotative formation test having a control valve operated by vertical movement, as there is less possibility of a rotating tester becoming jammed in the borehole.

Briefly, a preferred form of the present invention, as applied to and including a formation tester of the above-preferred type, consists of a choke and telescopic valve-operating mechanism and drilling mud discharge ports. The

upper portion of the device comprises a compound valve mechanism by which the axial passage within the device and tubing may be opened to allow fluid flow upward or closed to trap a formation sample below the mechanism and by which circulating passages in the wall of the device may be opened to allow egress of mud fluid to kill the well, prevent sticking of the drill string in the borehole, or for any other purpose.

The construction of an apparatus forming a preferred embodiment of the present invention will be readily understood from the following description taken in reference to the attached drawings, wherein:

Referring to Figure 1 of the drawing, the lower portion is composed of a number of elements as follows:

A hollow cylindrical body 1, partly shown also in Figure 2, has an external thread 2 and an internal thread 3 at its lower end. Threaded onto the external thread 2 is a retaining nut 4, holding a packing element 5 and a clamp 6, fitted to the exterior of the hollow cylindrical body 1. The clamp contains drilling mud discharge ports 7 in its lower portion, and holds in place an outer casing or tubing 8, which with the hollow cylindrical body 1 forms an annular space for passage of drilling mud to the discharge ports 7. The bore through the body 1 is enlarged above the bottom internal thread to permit of the installation of the control valve assembly, which consists of a valve seat 9 threaded into the body 1, a valve 10, a spring 11 acting to hold the valve 10 in contact with the valve seat 9 and provided with a retainer collar 12 and a lock pin 13. This control valve assembly defines the lower end of the sample-trapping chamber.

Into the bottom female thread 3 is threaded the rotating thrust member 14, which consists of a cylindrical member having an axial bore and a flange 15 on its lower end.

The rotative member 14 fits within a stationary member consisting of a hollow cylindrical housing 16, with an external thread 17 at its upper end and at the lower end a seat or shoulder 18 having an axial opening. Into the internal thread 19 of this opening, is threaded the hollow adaptor nipple 20. To the upper end of stationary member 16 is threaded the retaining collar 21, this latter also being threaded at its upper end to take the gland nut 22.

Within the housing and seated against the bottom internal shoulder 18, is a ball thrust race 23 with a heavy spring 24 between the ball race and flange 15 of the thrust member 14. Reten-

tion of the lubricating medium and exclusion of a well fluid from the interior of the stationary housing is maintained by packings 25 and 26.

- Threaded into the upper end of the adaptor nipple 20 is the hollow guide mandrel 21, which is fitted at its upper end with a combination choke and valve thrust member consisting of nipple 28 and choke member 29 holding between the flanges thereon stop collar 30 and packing 26.
- 10 At the outer end of choke member 29 is fitted the rotating thrust head 31 and thrust ball bearing 32.

Into the lower end of adaptor nipple 20 is threaded the packing elements consisting of the central hollow mandrel 33, having both an internal thread 34 and an external thread 35 at its lower end. Onto the outer end thread 35 is screw locking collar 36, which retains in place the washers 37, 38, 39, and 40, rigid packing rings 41 and a hollow expansible auxiliary packer 43, provided with a dividing diaphragm 42, said auxiliary packer being made of rubber, canvas, or similar resilient material and having its lower end attached to lock collar 36 by a cap washer 44 and screws 45, or by other suitable means. Openings 46 and 47 to the top and bottom of the two sections of packer 43 are provided for the subsequently described purpose.

30 Into the internal thread 34 at the lower end of the lower portion may be screwed the usual perforated closed end nipple 68. A bottom hole pressure recording bomb, temperature recorder, or any other desired instrument may likewise be attached to the formation tester at this or any other point below the packer in a manner understood by those familiar with the art.

Referring to Figure 2 of the drawing, the upper portion containing the upper half of the trapping formation tester comprises a hollow tubular body 48, which is attached to the hollow cylindrical body 1 by means of tool joint pin 49 and tool joint box 50 joined directly together or joined by means of drill pipe or other suitable connecting tubes, depending on the amount of sample desired.

45 Approximately midway of the bore of tubular body 48 is a restriction 51 having a valve seat 52 on the lower side. A threaded valve seat member 53 is screwed in at some distance below valve seat 52, and has within it a valve 54, valve spring 55, and locking collar 56.

Above this valve assembly, is a hollow piston 57, having a seat 58 at its upper end within which seats a valve 59 retained by a spring 60 and locking collar 61. The upper external edge of piston 57 forms a valve face 62, which is normally held against the body seat 52 by a spring 63, bearing on the lower end of piston 57 and valve seat 53. In the wall of the tubular body 48, are ports 64, normally closed by the piston 57.

In order that the valves in the compound valve mechanism open and close in suitable order, it is preferable that the relative strengths of coil springs be such that spring 63 is stronger than spring 55, which in turn is stronger than spring 60.

Surrounding the tubular body 48 is the continuation of the outer casing 8, which extends above the ports 64 in said tubular body 48 and is attached thereto by means of a threaded coupling 65 and threaded connections 66 and 67 on the casing 8 and tubular body 48, respectively.

In operation, the assembled tester is attached to the drill or tubing string by tool joint box 68 75 and is lowered into the well, until the expansible

rubber packer assembly enters the rat hole and the solid packer 41 comes to rest on the rat hole seat.

On placing further weight upon the drill stem, the rotative telescopic section 14 moves downwards, compressing spring 24. The valve retaining collar 12 of the control valve assembly is forced into contact with the ball bearing thrust head 31, which arrests the downward motion of valve 10. Continued downward motion forces 10 the valve seat 9 away from the valve 10, thus opening the lower end of the tool to the well pressure below the packer.

On the well starting to flow, the fluid passes up through the tubes 33 and 21, the choke 29, 15 valve seat 9, and around valve 10, and mounts in the drill stem until it encounters valve 54 of the compound valve mechanism. The pressure of the fluid forces this off its seat 53, passes through the hollow piston 57 and encounters the 20 second valve 59, which, in turn, is forced open, allowing the fluid to enter the drill stem above the compound valve mechanism.

On relieving the weight on the drill stem, the above-described operations are reversed. The 25 telescopic section 14 is moved upwards, aided by the heavy spring 24; the valve assembly (elements 9 to 13) is withdrawn from the thrust head 31, and the valve 10 is permitted to close under the force of its spring 11, thus trapping the bottom hole sample within the drill pipe between the lower and the upper valve assemblies, the valves in the latter being automatically closed by their spring as soon as the control valve is shut.

Should it be found desirable to rotate the apparatus during the taking of the sample, this may be done whether the tool is in the open or closed position. In the open position (right half cross section) the thrust between the stationary 40 and rotative elements is taken up by thrust ball bearings 23 and 32, but in the closed position (left half cross section), the thrust is taken up only by thrust ball bearings 23, locking collar 12 not being in contact with thrust head 31, thus relieving the bearing 32 of all thrust. In either case the drill or tubing string, together with parts 1—15, 23, 24, 31, 32, 48—67 and 69 connected thereto is allowed to rotate, while the packer 41, together with parts 16—22, 25—30, 33—40, 42—47 and 68 50 connected thereto, remains stationary.

Should the well become lively, or for any other reason it be found desirable to circulate mud fluid, this can be accomplished before, after, or during a test. On forcing mud fluid down the 55 drill stem, it continues downward until it encounters the piston 57 and valve 59 in the tubular body 48. Should the valve 59 be open, the mud fluid pressure forces it shut, thus trapping the bottom hole sample, should there be fluid between the upper and lower valve assemblies.

A further increase in pressure, sufficient to overcome the resistance of spring 63 plus any pressure below the piston 57, forces this latter downward along with valve 59 and seat 58, thus 65 uncovering ports 64 and permitting the passage of fluid from within the drill stem through the annular space or conduit between the outer casing 8 and bodies 48 and 1, and out through the discharge ports 7 to the well and thence to the 70

Normally, the auxiliary expansible packer 43 is inoperative when the solid packing element 41 makes a tight connection on the rat hole seat. Should, however, this seat leak, then the well 75

fluid, passing upward from below the auxiliary packer, in attempting to pass out around the solid packer seat, enters within the lower section through the openings 47 and forces it to expand 5 outward, thus making a tight connection with the walls of the rat hole. Likewise, a tight connection is maintained if the pressure differential is positive in the downward direction. For instance, when the mud pressure in the hole is 10 higher than the formation pressure, fluid passing by the solid packer seat enters the openings 46 of the upper section of the expandible packer and forces it outward to make a seal.

Although the above description of our preferred embodiment shows the device of the present invention as co-operating with a rotative formation having a control valve operated by vertical movement, it is to be understood that this device may be employed with other types of formation testers, such as the stationary type having rotary-operated control valves, without departing from the spirit of the present invention.

I claim as my invention:

1. In a formation tester, a tubular string, a 25 tubular stem member fitted for rotational and telescoping motion with regard to the lower end of the string, a packer rigidly mounted around said member, said member opening to the borehole below the packer, a choke member rigidly attached to the stem member within the upper 30 end thereof, a normally closed valve structure rigidly attached to the string within the lower end thereof, spring controlled means actuated by the pressure of said choke member for opening 35 said valve when the string is telescoped with regard to the stem member, an annular conduit around the tubular string, ports near the lower end of said conduit opening to the borehole above the packer, ports opening from said conduit to 40 the inside of the string above said first ports, a piston mounted for a limited axial motion within the string masking said upper ports, a valved

passage in said piston, and means for opening said upper ports and closing said valved passage by applying fluid pressure to said piston.

2. In a formation tester, a tubular string, a 5 tubular stem member fitted for rotational and telescoping motion with regard to the lower end of the string, a packer rigidly mounted around said member, said member opening to the borehole below the packer, a choke member rigidly attached to the stem member within the upper 10 end thereof, a normally closed valve structure rigidly attached to the string within the lower end thereof, spring controlled means actuated by the pressure of said choke member for opening 15 said valve when the string is telescoped with regard to the stem member, a thrust bearing on said choke member in contact with said valve structure for permitting a rotational motion of said valve structure with regard to said choke member when the string is telescoped with regard 20 to the stem member, an annular conduit around the tubular string, ports near the lower end of said conduit opening to the borehole above the packer, ports opening from said conduit to the inside of the string above said first ports, a 25 piston mounted for a limited axial motion within the string masking said upper ports, a valved passage in said piston, and means for opening 30 said upper ports and closing said valved passage by applying fluid pressure to said piston. 30

3. The device of claim 1, having anti-friction means between the packer member and the lower end of the tubular string fitted for rotational motion with regard to said member.

4. The device of claim 1, having an auxiliary 35 packer mounted on the tubular member supporting the main packer, said auxiliary packer comprising a flexible annular envelope having perforations opening to the borehole space below the main packer.

40

MAX L. JOHNSTON.
